COLLAPSIBLE UTILITY STOOL AND THE LIKE
 Christos G. Alexiou, 6758 Yolanda Ave., Reseda, Calif.
 Filed Sept. 21, 1960, Ser. No. 57,577
 3 Claims. (Cl. 248—431)

The invention relates to collapsible stools and the like devices, and more particularly to utility apparatus adapted for securing means whereby same may be easily folded into a compact form and then stored when not in use, and also for allowing same to be carried when required, and in addition for allowing same to be automatically released from its folded position and into a usable and serviceable stool.

Manifestly, an object of the invention is to provide a stool, having a stool seat and at least three leg members extending therefrom, wherein at least one of said leg members is pivotally mounted and secured at the underside section of said seat, while each of the remaining leg members has a resilient or contractive means associated therewith, for connecting each leg and said underside section of said seat and thereby for holding said leg members in position, and in addition, said leg members having a suitable collar means disposed at an approximately half length of said legs which is adapted for conjoining said leg members at one point of intersection and thereby holding said legs firmly in place and position with the leg ends spread into a suitable pattern and when said stool seat is in use.

Another object of the invention is to provide said underside section of said stool seat with means, adapted for locking and for holding said leg members in place and when same are in a parallelly extended position.

A further object of the invention is to provide said stool seat with means adapted for convenient handling thereof and said leg members, and when same are in a parallelly collapsed position.

Another object of the invention is to provide said stool seat in a suitable artistic pattern having a suitable cover therefor, for securing a pleasant appearance for said stool seat.

A further object of the invention is to provide said leg members of said utility stool with suitably arranged telescoping extensions, adapted for securing variable heights for said stool seat when in use, and also having suitable locking means therefor, so that said telescoping leg members may be held securely in place when in an extended position.

The invention also has for its objects to provide such means that are positive in operation, convenient in use, easily installed in a working position and easily disconnected therefrom, economical in manufacture, relatively simple, and of general superiority and serviceability.

Other and further objects and advantages of the invention, as will hereinafter more fully appear, I attain by the construction herein shown on the drawings and described in the specification, forming a part of the application.

Reference is had to the accompanying drawings in which the similar reference characters, denote the same parts.

In the drawings:

FIG. 1 shows a vertical side elevational view of the utility stool.

FIG. 2 shows the underside section of said utility stool, taken from the bottom of FIG. 1, and showing the leg members in extended position.

FIG. 3 shows the utility stool in a slightly enlarged form and in a vertical position, showing the leg members held parallelly in place.

FIG. 4 shows a vertically side view of the utility stool, showing same when taken from the right of FIG. 3.

2

FIG. 5 shows a fragmentary and a vertically sectional view of the leg member, provided with a retractable resilient unit member for holding the leg end against the stool seat.

5 FIG. 6 shows a plan view of the conjoining collar for holding the leg members in an angular position.

FIG. 7 shows a vertically sectional view of the conjoining collar, taken on the line 7—7 of FIG. 6.

FIG. 8 shows the underside plan view of said utility stool, similar in position as shown in FIG. 2, and showing the position of a handle in a modified form.

Describing the invention more in detail, in its broader aspects, said invention comprises a stool generally designated by numeral 2, which consists of a stool seat plate 4 and a plurality of downwardly extending leg members 6 which are tubular in structure and held in an conjoined position by means of a collecting collar member 8.

Said stool seat plate 4 is made out of suitable material having a special design or pattern for providing an artistic appearance and to be comfortable when in use, said plate 4 is also provided with a suitable hand slot or handle 10, so that said stool may be easily handled when required.

The underside surface section 12 of said seat plate 4 is provided with a hinge 14, of which one hinge plate is firmly secured upon said surface section 12 by means of suitable fasteners, while the other hinge plate 18 of said hinge is attached to a tubular sleeve 20, which is connected to and extends from the upper end of one of said leg members 6 and thereby forming a hinged leg member 22.

The mid-section 24 of said hinged leg member 22 is provided with said collecting collar member 8, the purpose and the operation of which will be presently described and which is mounted thereon and held in place by means of a pivot pin member 25.

Equally spaced at the underside surface section 12 of said seat plate 4 and away from said hinge member 14, are provided suitable anchor pins 26, each of which is allowed to pass through a suitable depression or pocket section 28 and to which the upper end of a resilient member 30 is attached, said resilient member may, if so desired be made in form of a tension spring, elastic rubber or the like.

The outwardly extended end of said resilient member 30 is slidably positioned within the upper tubular end section 32 of the supporting leg members 34 and 36, each end thereof is held in place and position by means of a mounting pin or rod 38, so that the tension of each resilient member 30 may be allowed to force and draw said upper end sections 32 of said supporting leg members 34 and 36 against and into the respective pocket sections 28 thereby holding same tightly and firmly in place and position.

Each supporting leg member 34 and 36 is held in a conjoined position by means of said collecting collar member 8 at the respective mid-sections thereof which are arranged to slide in the respective sockets or flutes 50, while said collar member 8 is held secured on said hinged leg member 22, thus allowing the extended lower leg sections 40, 42 and 44 to be spread triangularly for holding said stool seat plate 4 in position and for use. Each leg end is provided with a suitable rubberized cap 46 for preventing said stool from slipping when used and employed on smooth or polished surfaces.

65 In structure said collecting collar member 8 is provided with a plurality of angularly disposed sockets or flutes 50, which are positioned conjointly at the center section thereof, the number of flutes being equal to the number of said leg members employed, said flutes conjointly positioned will allow said leg members to slide and interlock together and for causing said leg members to be

held at all times tightly and in an angular position, as shown. In close proximity to said tubular sleeve 20 a suitable sliding bolt 52 is provided, allowing the outwardly extending end thereof to engage the tubular outer and upper section 54 of said tubular sleeve 20 and thereby holding and locking said leg member 6 when in a collapsed position, as shown in FIGS. 3 and 4.

It may also be noted that said leg members 6 may, if so desired, be made telescoping and in sections, and be made extendable when required for securing a higher position for said stool seat plate 4, and that a suitable locking means may be provided therein for holding the extended telescoping leg members in place.

Also, in order to hold said leg members 6 in a collapsed position, said stool seat plate 4 is provided with a holding strap 56 for allowing a convenient handling of said stool when in collapsed position and not in use.

In operation, when it is desirous to use said stool 2 and when said stool is in a folded and collapsed position, said holding strap 56 is unfastened and then the sliding bolt 52 is removed from its engaging position, thereby allowing said supporting leg members 34 and 36 to slide upwardly toward the underside section 12 and into their outwardly spread positions, which is caused by the inward pull and force of said resilient members 30 and the outward movement of said leg members 34 and 36 and which will also force said hinged leg member 22 into its proper position, while said collecting collar member 8 guides and holds said leg members 6 at their respective mid-sections 24, thereby allowing said stool to be made serviceable and for use.

For securing a pleasant appearance, said stool seat plate 4 may, if so desired, be provided with a suitable cloth or cushion covering, which is held thereon by means of an elastic band, as shown in FIG. 1.

In order to facilitate the manufacture of the utility stool, said leg members 6 are made entirely of a suitable tubing material as shown, while said seat plate 4 may be made out of wood or be formed and pressed out of light-in-weight material, thereby providing an article of manufacture which is not only inexpensive to produce in quantities, but also providing an article of manufacture that is pleasant in appearance, useful and easy to handle.

While I have thus described the invention with great particularity, it will be clear that the same may be modified throughout a wide range.

I accordingly do not propose to be limited to the exact details of construction herein shown on the drawings and described in the specification, but reserve the rights in practice to make any and all necessary changes and modifications therein, which may come within the scope of the appended claims.

I claim as my invention:

1. In a utility stool of the class described comprising in combination, a stool seat plate, a plurality of extendable leg members connected to and mounted at the underside surface section of said stool seat plate of which one leg member is hingedly secured thereto, said plurality of leg members extending downwardly and conjoining at their respective mid-sections, a collecting collar member secured to said hinged leg member and disposed at the mid-section thereof for conjoining said remaining extendable supporting leg members and for holding same in a tight conjoined position, a contractible resilient member in at least two of the upper ends of said plurality of leg members for holding same in position and against the underside surface section of said stool seat plate and when said utility stool is in use, and a locking bolt at the underside surface section of said stool seat plate positioned oppositely and in line with said hingedly secured leg member for holding said plurality of leg mem-

bers in a parallelly extended position and locked in place when said utility stool is not in use.

2. In a utility stool of the class described, comprising the combination of, a stool seat plate made out of pliable material, depressions in the underside surface section of said stool seat plate, an anchor pin passing through each depression, a hinge member mounted at said underside surface section and disposed in equidistant position from said depressions, a tubular sleeve connected to said hinge member, a hinged and extendable leg member connected to said tubular sleeve and extending downwardly from said stool seat plate, a resilient member connected at one end thereof to each anchor pin and extending outwardly from its mounted position, a pair of extendable supporting leg members the upper end of each being connected to the respective extended end of said resilient member and held at a tension, for holding the upper end section of said extendable supporting leg members tightly and firmly in said depressions and against the underside surface section of said seat plate, a mid-section in said pair of extendable supporting leg members including said hinged and extendable leg member, for providing a common crossing point for said conjointly extendable leg members, a collecting collar means mounted on said hinged extendable leg member and disposed at said mid-section thereof for receiving said pair of said extendable supporting leg members and for holding same at their respective mid-sections in a conjoint position, a slidable bolt lock mounted at the underside surface section of said stool seat plate for engaging said tubular sleeve of said hinged extendable leg member and for holding said remaining extendable leg members in a parallelly locked position when disengaged from their normally usable place and when said stool is not in use, and rubberized caps at the extended end of each extendable leg member for providing a surface grip and for preventing said utility stool from sliding over smooth surfaces.

3. In a utility stool of the class described comprising the combination, of a stool having a stool seat plate made of suitable material and thickness, a plurality of supporting leg members extendable to a suitable length and below said stool seat plate, wherein, one leg member being hingedly mounted at the underside surface section of said stool seat plate, a resiliently extendable and contractable member mounted at said underside surface section of said stool seat plate in equidistant position with relation to the remaining leg members and connecting each at the upper end thereof, a collecting collar mounted on said hingedly mounted leg member for slidably engaging and conjointly holding said remaining leg members in an interlocked position, and a sliding bolt mounted at said underside surface section of said stool seat plate for engaging said hingedly mounted leg member and thereby holding all of said leg members together in a parallelly extended and locked position when said stool is not in use.
